UNITED STATES PATENT OFFICE.

ROBERT BENJAMIN WILLIAMS, OF INVERCARGILL, NEW ZEALAND.

MACHINE FOR WASHING CLOTHES.

SPECIFICATION forming part of Letters Patent No. 596,037, dated December 21, 1897.

Application filed September 6, 1895. Serial No. 561,657. (No model.) Patented in New Zealand February 11, 1895, No. 7,421; in New South Wales September 9, 1895, No. 6,045; in Victoria September 11, 1895, No. 12,504; in Queensland September 11, 1895, No. 3,119; in England October 3, 1895, No. 18,500, and in South Australia June 1, 1896, No. 4,292.

To all whom it may concern:

Be it known that I, ROBERT BENJAMIN WILLIAMS, a British subject, residing at Invercargill, in the Colony of New Zealand, have 5 invented a new and useful Machine for Washing Clothes, of which the following is a specification.

The invention has been patented in England, No. 18,500, dated October 3, 1895; in 10 New Zealand, No. 7,421, dated February 11, 1895; in New South Wales, No. 6,045, dated September 9, 1895; in Victoria, No. 12,504, dated September 11, 1895; in Queensland, No. 3,119, dated September 11, 1895, and in South 15 Australia, No. 4,292, dated June 1, 1896.

My invention relates to improvements in machines for washing clothes, and has for its objects providing a cheap and handy machine which shall effectually wash clothes with little expenditure of labor, have few parts, be 20 portable, and easily operated.

I carry out the objects of my invention by making my machine with a cylinder mounted upon journals over a trough. A suitable handle is supplied for imparting motion to the cylinder and a lid for filling and emptying the same. The trough has an orifice at one 25 end, at its lowest part, for emptying out water.

Within the cylinder I provide chains, which 30 are placed loosely among the clothes, so that when the cylinder is revolved the friction of the links gives the necessary rubbing action.

In order that my invention may be more clearly understood by one skilled in the art 35 to which it appertains, I will now describe the same in detail, and in doing so shall refer to the accompanying drawings.

Similar letters refer to similar parts throughout the views.

40 Figure 1 is a side elevation of my machine, partly in section, on line A B, Fig. 2. Fig. 2 is an end elevation of the same, partly in section, on line C D, Fig. 1. Fig. 3 is a frame used when emptying the machine. Fig. 4 is 45 a view of the grating partially collapsed.

Cylinder a, which is made of wood by preference, is mounted upon journals a' and a'', working in bearings a³ and a⁴. Beneath the cylinder I fix a trough b, preferably of wood 50 for cheapness, and having an orifice b' for the escape of waste water. The cylinder a and trough b are supported upon legs c, and to

the top of these are attached the bearings a³ and a⁴ by bolts a⁵ and a⁶.

Lid a⁷ of cylinder a moves upon hinges a⁸ 55 and when closed is fastened by thumb-nuts a⁹. Iron band a¹⁰ connects together the timber of which lid a⁷ is made, and bands (a¹¹) hold together the parts forming the cylinder.

The handle d is securely fitted to the produced end a¹² of journal a' for imparting motion to cylinder a.

Within cylinder a I place lengths of chain f, laid loosely between layers of clothes, so that when handle d is turned cylinder a, with 65 its contents, is revolved. Friction of the chains among the clothes gives the necessary rubbing action required when washing.

When it is desired to empty out the contents of cylinder a, lid a⁷ is opened and grating g placed inside and across the opening, the battens g' being revolvable around bolts g³ upon batten g² to allow of their being inserted while closed together and afterward spread apart. The cylinder is then turned 75 so that its mouth is downward, when the water will run out and the clothes and chains f be retained in the cylinder a, which is then reversed to bring the opening upward, so that the clothes and chains may be taken out. 80

The grating is shown in place in Fig. 2, being shown in dotted lines.

I am aware that prior to my invention washing-machines have been made which revolve on bearings. I therefore do not claim such 85 machines broadly; but

What I do claim as my invention, and desire to secure by Letters Patent, is—

1. In combination with the rotary cylinder of a washing-machine having an opening, a 90 collapsible grating therein, substantially as described.

2. In combination with the cylinder of a washing-machine, a chain or chains arranged therein among the clothes to produce a rubbing action thereon, substantially as 95 described.

In witness whereof I have hereunto set my hand in presence of two witnesses.

ROBERT BENJAMIN WILLIAMS.

Witnesses:

EUSTACE RUSSELL,
ROBERT AITKIN.
